A CORPORATION OF MASSACHUSETTS.

BILL INDEXING AND SORTING DEVICE.

1,009,447.

Specification of Letters Patent. Patented Nov. 21, 1911.

Application filed June 10, 1908. Serial No. 437,681.

To all whom it may concern.

Be it known that I, GILBERT C. SHEPHERD, a citizen of the United States, and a resident of the borough of Brooklyn, in the city of New York, county of Kings, and State of New York, have invented certain new and useful Improvements in Bill Indexing and Sorting Devices, of which the following is a specification.

10 My invention relates to a bill indexing device. A system of preparing bills or statements has lately come into use and the object of my invention is to produce a device which will facilitate in the preparing and handling 15 of such statements, whereby time and annoyance will be saved and at a very small cost. At the present time many business concerns prepare their bills or statements in duplicate, triplicate and so forth and then separate 20 the several copies, sending them to the debtor at desired intervals and using other copies for record and so forth. My invention relates to the formation of the bills or sheets themselves, and my invention is particularly useful where statements are temporarily filed in a holder and items added 25 to them, say during the month if bills are sent monthly, and at the end of the month the copies are disposed of as referred to.

30 My invention includes a bill sheet for such sorting having stepped tabs so arranged as to aid in the assorting and handling of the sheets.

In the drawings forming a part of this application, Figure 1 is a perspective view of my improved device, Fig. 2 is a perspective view of some of the bill sheets, Fig. 3 is a perspective view showing a bill sheet and Fig. 4 is a similar view of another sheet.

40 The sheets especially adapted for this device and system are as follows: A manifold sheet is provided with suitable headings printed thereon, ruling and the like, which is folded upon itself any number of times, 45 according to the number of copies of the bill or statement that are to be made and in the examples which I have here shown they are folded to provide three blanks, whereby the bill may be made out in triplicate.

50 By reference to Fig. 3 it will be seen that the sheet 9 is folded along perforated lines 10 and 11 so that there is provided the two full length folds 12 and 13 and a shorter fold 14, though the proportions of these folds

may be altered to suit any requirements. 55 The sheets with the several folds are, until severed, a unit and it would be difficult to select any one of them from the group owing to there being several folds. To avoid confusion and assist in the handling of the 60 sheets I have provided stepped tabs. The sheet shown in Fig. 3 for instance, is say the front one of the group to be used in the receptacle, and there is provided at the upper edge a stepped tab 15 on fold 12 and a 65 similar tab 16 on fold 13. In making the tabs I contemplate making them so that the various tabs on the folds of any given sheet will overlap and they should coincide so that when handling the sheets, by grabbing 70 the tab, all or at least several of the folds of that one sheet will be gripped by the fingers together, to withdraw the sheet from the pack. Fig. 4 illustrates a sheet which would come near the rear, and in this case 75 the tab may come on all three folds. As shown in Fig. 1, the sheets when placed in the receptacle have their various tabs stepped, that is, the tab of each successive sheet extends along farther than the preceding one 80 and a leader sheet 17 is provided at the rear, which extends beyond the stepped tabs and is provided with indicating means, such as letters or figures 18. By taking hold of the tab opposite the letter or numeral representing the statement of a certain debtor, 85 the statement desired may be readily removed and any matter added and it is then returned. Instead of using a leader sheet, 90 I can place the indicating means, such as the numerals, on the stepped tabs themselves, as shown in Fig. 2, though I prefer the former arrangement as it is more readily carried out.

I believe I am the first to use a sheet 95 which is folded upon itself and every one of the folds of which has a tab. For instance the sheet shown in Fig. 4 might be used without the fold 12 and still have some of the advantages of my invention, so long as 100 the tab 16 extends above the sheet 14 and so long as the tab is on one of the free edges of the sheet as distinguished from the folding edge.

Having described my invention what I 105 claim is:

1. In a billing device, a plurality of separate sheets, each vertically folded upon

itself, a plurality of folds of the said sheets having end tabs on their upper edges extending from the folds, the tabs of the several folds of a sheet coinciding in position with each other, and the tabs of several sheets being stepped at varying distances from said vertical folds, whereby all the folds of a sheet may be selected as a unit.

2. In a billing device, a plurality of separate sheets each folded upon itself near its center, a plurality of folds of each sheet having tabs on their upper edges extending

from the folds, the tabs of the several folds of a sheet coinciding in position with each other and the tabs of the several sheets being stepped, whereby the folds of a sheet can be selected as a unit, each sheet having a shorter narrow fold at the opposite end. 15

Signed at the city, county and State of New York this 30th day of May, 1908.

G. C. SHEPHERD.
